(57) CLAIM

The ornamental design for a set of reconfigurable sofa pieces, as shown and described.

DESCRIPTION

FIG. 1 is a perspective view of a set of reconfigurable sofa pieces, comprised of pieces A, B, C, D and E in the first combined state, showing my new design;

FIG. 2 is a perspective view of the pieces A, B, C, D and E in the second combined state;

FIG. 3 is a perspective view of the pieces A, B, C, D and E in the third combined state;

FIG. 4 is a perspective view of the pieces A, B, C, D and E in the fourth combined state;

FIG. 5 is a perspective view of the pieces A, B, C, D and E in the fifth combined state;

FIG. 6 is a perspective view of the pieces A, C, D and E in the sixth combined state;

FIG. 7 is a perspective view of the pieces B, C and E in the seventh combined state;

FIG. 8 is a front, right, top perspective view of the sofa piece A, showing my new design, with the rest of the sofa pieces removed for ease of illustration;

FIG. 9 is a rear, left, bottom perspective view thereof;

FIG. 10 is a front elevational view thereof, the rear elevational view is identical;

FIG. 11 is a left side view thereof, the right side being a mirror image of FIG. 11;

FIG. 12 is a top plan view thereof;

FIG. 13 is a bottom plan view thereof;

FIG. 14 is a front, left, top perspective view of the sofa piece B, showing my new design, with the rest of the sofa pieces removed for ease of illustration;

FIG. 15 is a rear, right, bottom perspective view thereof;

FIG. 16 is a front elevational view thereof, the rear elevational view is identical;

(Continued)

FIG. 17 is a left side view thereof, the right side view is identical;
 FIG. 18 is a top plan view thereof, the bottom plan view is identical;
 FIG. 19 is a rear, left, bottom perspective view of the sofa piece C, showing my new design, with the rest of the sofa pieces removed for ease of illustration;
 FIG. 20 is a rear, left, bottom perspective view thereof;
 FIG. 21 is a front elevational view thereof, the rear elevational view being a mirror image of FIG. 21;
 FIG. 22 is a left side view thereof;
 FIG. 23 is a right side view thereof;
 FIG. 24 is a top plan view thereof, the bottom plan view is identical;
 FIG. 25 is a front, right, top perspective view of the sofa piece D, showing my new design, with the rest of the sofa pieces removed for ease of illustration;
 FIG. 26 is a rear, left, bottom perspective view thereof;
 FIG. 27 is a front elevational view thereof, the rear elevational view being a mirror image of FIG. 27;
 FIG. 28 is a left side view thereof;
 FIG. 29 is a right side view thereof;
 FIG. 30 is a top plan view thereof, the bottom plan view is identical;
 FIG. 31 is a front, right, top perspective view of the sofa piece E, showing my new design, with the rest of the sofa pieces removed for ease of illustration;
 FIG. 32 is a rear, left, bottom perspective view thereof;
 FIG. 33 is a front elevational view thereof, the rear elevational view is identical;
 FIG. 34 is a left side view thereof, the right side view is identical; and,
 FIG. 35 is a top plan view thereof, the bottom plan view is identical.
